UNITED STATES PATENT OFFICE.

EDWIN W. HESS, OF CRESO, IOWA.

DISPLAY-CABINET.

1,179,831.

Specification of Letters Patent. Patented Apr. 18, 1916.

Application filed September 12, 1914. Serial No. 861,412.

To all whom it may concern:

Be it known that I, EDWIN W. HESS, a citizen of the United States, residing at Cresco, in the county of Howard and State 5 of Iowa, have invented certain new and useful Improvements in Display-Cabinets, of which the following is a specification, reference being had to the accompanying drawings.

10 This invention has for its primary object an improved construction of device for use in refrigerating and attractively displaying fruits, flavors, liquors or the like in cafés, restaurants, or other places and to supply 15 cold water entirely free from contamination from or contact with melted ice, the parts being so constructed and arranged that electric light bulbs will shine from below through glass containers holding fruits or 20 other food articles and also against the liquid containers or bottles back of which a mirror is placed which separates the ice containing compartment from the food and drink holding compartment and at the same 25 time enhances the attractiveness of the display. And the invention also aims to generally improve devices of this kind so as to render them more attractive and more commercially desirable.

30 With these and other objects in view, as will more fully appear as the description proceeds, the invention consists in certain constructions, arrangements and combinations 35 of the parts that I shall hereinafter more fully describe and claim.

For a full understanding of the invention, reference is to be had to the following description and accompanying drawing, in which,

40 Figure 1 is a front elevation of a refrigerating and display device embodying the improvements of my invention. Fig. 2 is a transverse sectional view, the section being taken on the line 2—2 of Fig. 1.

45 Corresponding and like parts are referred to in the following description and designated in all of the views of the accompanying drawing by like reference characters.

50 Referring to the drawing, the numeral 1 designates a case or cabinet which may be of any desired size, shape, or proportions of the parts and formed of any desired substance or materials, and of any desired construction, except as hereinafter noted. In the 55 rear upper portion of the cabinet is the ice

receiving compartment 2, the bottom of which is defined by a coil 3 on which the ice is adapted to rest, said coil being fed with water at one end by means of the supply 60 pipe, (not shown) which extends up through the bottom of the cabinet and being provided at its discharge end with a faucet 5 underneath which is a drain cup or receptacle secured to the end wall of the cabinet 1 and 65 communicating with a drain pipe 7 within the cabinet and extending down through the bottom thereof. Preferably the drain pipe 7 is provided with a trap 8 of any desired construction and it communicates, by means 70 of a relatively short length of pipe 9 with a tray 10 disposed horizontally within the cabinet just underneath the coil 3 on which are supports 11 for the coil. This pan or tray 10 is designed to catch the drippings 75 from the melting ice and convey the same to the pipe 9 and thence to the drain pipe 7.

Immediately in front of the ice receiving compartment 2 and like said compartment, extending longitudinally the full length of 80 the cabinet, is the food and drink displaying and holding compartment 12. The rear of this compartment is divided by a vertically disposed longitudinally extending mirror 13 which separates this compartment from the 85 compartment 2 and which is designed to assist in the attractiveness of the display of bottles on a longitudinally disposed shelf 14 and of fruit or the like in glass containers 90 15 that are inserted in openings 16 formed in a shelf 17 secured within the cabinet in the rear of the front thereof, as best illustrated in Fig. 2. Underneath the shelf 17 is a horizontally disposed shelf 18 for the support of the electric light bulbs 19 that are 95 separated and insulated from the remainder of the cabinet by means of partitions 20.

21 designates the lead wires to the bulbs and 22 an electric switch whereby the light may be controlled. Underneath the shelf 18 and drip pan or tray 10, is a relatively large refrigerating compartment 23 designed to hold goods to be kept cool but not displayed.

The front of the cabinet is formed with a plurality of ventilating openings 24 disposed in transverse registry with the bulbs 19. The cabinet is provided in its front with glass panels 25 through which the contents of the compartment 12 may be viewed, and it is provided in its top with doors 110 26 also having glass panels therein for the same purpose and also for the pur-

pose of admitting access to the interior of the compartment 12 for the removal or replacement of any of the articles designed to be held therein. Preferably all of these 5 panels are of double glass with an air space between so as to reduce to a minimum the liability of collection of moisture. At the rear the cabinet is provided an upper door 27 whereby access may be had to the ice 10 holding compartment 2 and a lower door 28 whereby access may be had to the refrigerating compartment 23.

From the foregoing description in connection with the accompanying drawings, the 15 operation of my improved refrigerating display cabinet will be apparent. In the practical use of the device, the ice contained in the compartment 2 and resting directly on the water coil 3, will keep the water cold 20 without the same coming in contact with or being contaminated by the ice and the articles contained within the compartment 12 will be very attractively displayed while they are refrigerated, by means of the light 25 cast up through the glass containers 15, the light being also shed upon the bottles on the shelf 14 and the reflected light enhancing the display to a material degree.

While the accompanying drawing illustrates what I believe to be the preferred embodiment of my invention, it is to be understood that the invention is not limited there- 30

to but that various changes may be made in the construction, arrangement and proportions of the parts without departing from 35 the spirit of my invention as defined in the appended claim.

What is claimed, is:

A display device including a cabinet provided with a display compartment having 40 transparent walls, a shelf mounted in said compartment and provided with a series of openings for the reception of transparent receptacles, electric lamps mounted within the cabinet beneath the respective openings in 45 the shelf, vertical walls separating the lamps from each other whereby their rays are concentrated upon the respective transparent receptacles, a sheet of mirror glass arranged in the cabinet and defining the rear wall of 50 the display compartment, and a second vertical supporting shelf arranged in parallel relation to the first shelf rearwardly thereof and contiguous to the mirror, said mirror reflecting the rays from the several lamps 55 upon the articles supported on the latter shelf.

In testimony whereof I hereunto affix my signature in the presence of two witnesses.

EDWIN W. HESS.
